UNITED STATES PATENT OFFICE.

RYOHEI KAGIWADA, OF WASHINGTON, DISTRICT OF COLUMBIA.

STRUCTURAL TOWER.

Application filed April 25, 1923. Serial No. 634,449.

To all whom it may concern:

Be it known that I, RYOHEI KAGIWADA, a subject of the Emperor of Japan, residing at Washington, in the District of Columbia, have invented certain new and useful Improvements in Structural Towers, of which the following is a specification.

My invention relates to the construction of structural towers in general, particularly of that type of towers, wherein the structure is normally subjected to a constant strain of a given magnitude acting in a fixed direction, besides the wind and other pressure caused by the elements, as well as torsional moments of considerable magnitude.

According to the standard practice, it has been customary to construct a tower of such description with a plurality of corner posts or columns which constitute the principal members required to sustain a greater part of the total load on the structure. But the imperfect features of such a construction are many, and have long been known to those who are versed in the art.

The customary use, for instance, of the material of a uniform section in manufacturing the main columns makes it unavoidable, especially in the case of high towers, that a larger part along its length should possess a greater size, and consequently a greater weight, than what is actually required. This results from the necessity of manufacturing them of a large enough section to take care of the maximum load the columns are designed to withstand. Because the distributed load at any point in the greater part of its length is smaller than the maximum that acts on the smaller portion of its longitudinal dimension, it has been unavoidable that the greater length of such a column should have a larger size than the necessary strength demands.

Still another cause of the excessive weight of a long column is the dimensional allowance given to the material used, which being done with a view of off-setting its slenderness that would result if the mathematical deductions were depended upon as a sole determinant of the ultimate size of its section. Such allowance or additional size would be totally unnecessary if it were possible to use the material having a proper size to correspond with the actual requirement at each section or length of the column. But, heretofore, it has not been possible to

do so in the face of economic and other considerations that have to be considered.

Besides, the usual construction does not lend itself in avoiding the use of idle members which function only when the strain acts in a certain direction, being absolutely useless and idle when the structure they compose is subjected to a strain in any other direction. Then, again, the secondary stresses which are statistically indeterminate, form a feature which has always been present in the calculation of this type of structure, and contributed in no small degree in causing a measure of uncertainty to creep into the design of a structural tower with respect to its ultimate strength, since more or less guess work had to be resorted to in the calculations.

Further, a tower of the type designed in accordance with the usual practice is far from being an ideal structure to withstand torsional moments, especially when they are applied with a suddenness that lowers the time constant so greatly that the strain assumes an enormous magnitude. This feature in the customary design is a grave imperfection, particularly in the case of towers for electric transmission lines and for similar purposes.

The essential object of my invention, therefore, is in providing a novel and efficient form of structural tower by adopting an improved construction, wherein the imperfect features of the customary construction reviewed in the foregoing paragraphs are eliminated, and at the same time, render both the design and construction greatly simple.

Other objects attained and superiority realized by my improved construction will be pointed out and particularly set forth in the claims.

To these ends, my invention comprises a construction which assures absolute avoidance of the idle members above referred to, by combining the constituent members in such a way as will distribute the total load on every member thereof, under all circumstances. My invention also makes it possible to design a tower so as to fulfill the requirements of the statistical deductions with an accuracy heretofore unattained, and to reduce the total weight of the structure to a minimum, while assuring a maximum ultimate strength with respect to the strain a

tower of the type mentioned is expected to bear.

In carrying out my invention, I construct the tower structure by mounting one upon another of a plurality of constructional units formed by two sets of horizontal members, each set of which forms a polygon and joined with each other, by a plurality of diagonal members.

- 10 These polygons, which may, or may not be of the same size, as desired, lie in two independent planes parallel to each other with a suitable distance between them. They are arranged to have a common vertical axis, around which one has a "lead" of 45°, with respect to each other. In other words, their relative positions around the common vertical axis is such that if one of them should be turned around, the axis through 15 20 25
- an angle of 45°, its vertical projection upon the plane of another polygon will, in case they are of the same size, form a congruent figure with the other; and that when the polygons are of different sizes, the said projection will form a polygon whose sides are parallel with those of the other.

By reason of the construction above described, it will be clearly seen that an apex of one polygon will be equidistant from the 30 35 40 apexes of the other polygons on either side of the former. Hence, all the diagonal members joining the apexes of one polygon with those of the second polygon will be of the same lengths, regardless of the number of sides in the polygon; and the resultant structure will present a form of polyhedron, bounded by a plurality of uniform sized lateral planes. This polyhedron constitutes what I term throughout this specification the constructional unit of my present invention.

In the drawings, like numerals of reference indicate similar parts in the several views, and wherein:

Figure 1 is a diagrammatic front elevation of one form of the tower, embodying my invention.

Figure 2 is a horizontal plan of the lower end thereof.

Figure 3 is an enlarged fragmentary elevation of the tower, showing one means of joining the structural units.

Figure 4 is a view somewhat similar to Figure 3, showing a slight modified form of means for connecting the adjacent structural elements comprising the tower.

Figure 5 is a side elevation of Figure 3, and

Figure 6 is a plan view of a gusset plate that may be employed in the joining of the structural elements.

In the case of the specific forms shown as an illustration of my improved construction and depicted in the accompanying drawings, the polygons are in the form of equilateral squares, such as $e-f-g-h$, and

$i-j-k-l$, Figure 2, composed of horizontal members, d , d , d , and d , and c , c , c , and c , respectively, Figure 1; these squares being joined at their apexes by diagonal members m , n , p , and q , etc., of a uniform length, in 70 such a way that the two squares are 45° apart from each other around the common axis. In this instance, my constructional unit presents the form of a decahedron.

By mounting a required number of these 75 units one above the other, any desired height of a tower may be attained. Also, by proportioning the size of the respective squares, the unit may be made to produce any required taper of the tower desired; or, 80 on the contrary, it may be made to form no taper, so that the diagonals may lie in their respective plane, perpendicular to that of the squares. It will, therefore, be seen that my invention provides a construction whereby 85 a tower of any desired height and shape may be formed.

In the ordinary construction, the diagonals or braces play no part in offering resistance to wind pressure or other forces. In 90 such cases, these members simply add to the weight of the tower, without in any way contributing to its strength. But in my improved construction, the use of such idle members has been totally avoided, and the 95 constituent members are so arranged and disposed, that each piece is effective at all times. By the elimination of the idle members, a considerable reduction is effected 100 in the total weight of the tower.

Furthermore, in my improved construction, the unit decahedron, in the specific form illustrated, and the polyhedron, covering all cases, being always composed of 105 triangular formations, the statistically indeterminate features are entirely absent, resulting in greater accuracy and certainty in design. By discarding the customary form of main columns and substituting therefor a series of diagonals of the size 110 properly proportioned to possess the strength required at each stage, the calculations of the structure is not only reduced to a great simplicity, but it can be made to faithfully conform with both the theoretical and 115 practical requirements.

It will also be clear to anyone versed in the art that the novel formation in my construction, gives the structure a resistance to twisting moments, far greater than would be possible in the customary design. This 120 is an especially important consideration in such towers as are intended to support electric transmission lines, or wireless antenna conductors, and in similar towers, 125 since the strain produced in a tower is sudden, and, in most cases, complex, as when a breakage occurs in one or more of the conductors it carries.

A modified form of joint adapted to ef- 130

fect economy in the cost of manufacture of a tower is shown in Figures 3 and 5. In the form shown, the bending of the materials is made unnecessary, the members being joined by the use of gusset plates 5 and 5' in Figure 3, and 5^a and 5^b in Figure 5, as shown. These figures also indicate how, by properly proportioning the length of the sides *d*, *d*, *c*, *c*, etc., of the squares 10 in the decahedron unit, the diagonals, *p*, *p*, etc., may be caused to lie in a plane perpendicular to that of the square.

In Figure 4, the diagonals are shown as being secured to the horizontal members 15 *d* and *c*, through the medium of gusset plates 6, shown more clearly in Figure 6, it being of course understood that these plates necessarily have to be slightly curved to engage around the apex of the polygons 20 formed by said horizontal members *d* and *c*.

Various modifications may be introduced in the construction to meet specific requirements, without deviating from the spirit of my invention, and I, therefore, desire that 25 the particular forms shown in the accompanying drawings shall not be construed to limit the scope of my invention in any way whatsoever.

Having thus described my invention,

what I claim as new, and desire to secure by Letters-Patent, is:

1. In a structural tower, the construction unit, consisting of a polygon composed of a set of horizontal members, a second polygon composed of a second set of horizontal members, the said pair of polygons being parallel to each other, and having a common axis, around which one of the polygons is disposed in respect to the other with a lead equivalent to one-half the angle subtended by the apex of said polygons, in combination with a plurality of diagonal members joining the said pair of polygons at their respective apexes and forming a 40 plurality of triangles with the horizontal members of the polygons, substantially as and for the purpose described. 35

2. A structural tower composed of a plurality of the constructional units set forth 45 in the claim 1, the said units being mounted one upon another, the horizontal members composing the polygons of each adjacent unit being common to each other, substantially as and for the purpose set forth. 50

In testimony whereof I affix my signature.

RYOHEI KAGIWADA.
